US0D1099024S

(12) **United States Design Patent** (10) Patent No.: **US D1,099,024 S**
(45) Date of Patent: ** Oct. 21, 2025

- (54) **CHARGING DEVICE FOR MEDICAMENT INFUSION PUMP DEVICE**
- (71) Applicant: **Beta Bionics, Inc.**, Concord, MA (US)
- (72) Inventors: **David Matthew Henderson**, Mission Viejo, CA (US); **Todd S. Ray**, Spokane Valley, WA (US); **Michael J. Rosinko**, Anaheim, CA (US); **Bryan Dale Knodel**, Flagstaff, AZ (US)
- (73) Assignee: **Beta Bionics, Inc.**, Irvine, CA (US)
- (**) Term: **15 Years**
- (21) Appl. No.: **29/776,662**
- (22) Filed: **Mar. 31, 2021**

CLAIM

The ornamental design for a charging device for medicament infusion pump device as shown and described.

DESCRIPTION

This invention was made with U.S. Government support under Contract No. DK120234, awarded by the National Institutes of Health. The Government has certain rights in the invention.

FIG. 1 is a front, first side, and top isometric view of a first embodiment of a charging device for medicament infusion pump device embodying the new design;

FIG. 2 is a front, first side, and top isometric exploded view thereof;

FIG. 3 is a rear, first side, and bottom isometric view thereof;

FIG. 4 is a rear, first side, and bottom isometric exploded view thereof;

FIG. 5 is a front view thereof;

FIG. 6 is a rear view thereof;

FIG. 7 is a second side view thereof;

FIG. 8 is a first side view thereof;

FIG. 9 is a top view thereof; and

FIG. 10 is a bottom view thereof.

FIG. 11 is a front, first side, and top isometric view of a second embodiment of a charging device for medicament infusion pump device embodying the new design;

FIG. 12 is a front, first side, and top isometric exploded view thereof;

FIG. 13 is front view thereof;

FIG. 14 is a rear view thereof;

FIG. 15 is a second side view thereof;

FIG. 16 is a first side view thereof;

FIG. 17 is a top view thereof; and,

FIG. 18 is a bottom view thereof.

The broken lines in the drawings are used to illustrate environmental structure and portions of the charging device for medicament infusion pump that form no part of the claimed design. The broken lines immediately adjacent to the claimed surfaces represent boundaries of the claim, which extends to the boundaries, but does not include the boundaries; the broken lines form no part of the claimed design.
